ARTICLE COUNTING MACHINE

Alten E. Whitecar, Westville, N. J., assignor to
Smith, Kline & French Laboratories, Philadel-
phia, Pa., a corporation of Pennsylvania

Application May 15, 1952, Serial No. 287,854

5 Claims. (Cl. 235—98)

1

This invention relates to an article counting machine and, more particularly, relates to such a machine used to separate articles, for example, envelopes, into groups having a certain desired count.

This invention provides a continuously operating article counting machine which, in a novel manner, eliminates any necessity for stopping the mounting machine when a group of the desired count has been formed.

It is, therefore, the broad object of this invention to provide an article counting machine suitable for counting the number of articles that have been placed into a group and which will operate continuously.

These and other objects of this invention will be made apparent from the reading of the following description in conjunction with the drawings, in which:

Figure 1 is a plan view of the article counting machine in accordance with this invention;

Figure 2 is a front elevation of the structure in Figure 1;

Figure 3 is a side elevation of the structure of Figure 1;

Figure 4 is a section taken on the plane indicated by the line 4—4 in Figure 1; and

Figure 5 is a section taken on the plane indicated by the line 5—5 in Figure 1 showing the article lifting mechanism in the elevated position.

Referring now to the figures, particularly Figure 1, an article counting machine 2 is provided with a base 4.

Referring now to Figure 5, a trip arm 6 is pivotally secured to a shaft 10. The trip arm 6 is positioned so as to be engaged by the upward movement of the envelopes shown at 8. The left-hand end of trip arm 6, as viewed in Figure 5, is pivotally secured to a lever 12 at 13. Lever 12 is pivotally secured to lever 14 which operates a conventional spring return ratchet counter 16. The counter 16 is secured to a pedestal base 18, which is in turn secured to base 4.

Trip arm 6 has a lever 20 fixedly secured to its top. A lever 22 has its right-hand end, as viewed in Figure 5, pivotally secured to the top of lever 20. Lever 22 has, at its other end, a forked end 24 which encompasses the upper portion of a lever 26, and is pivotally secured thereto. Lever 26 is fixedly secured to a shaft 28. Shaft 28 is supported by and is axially movable through bracket support member 29 (Figure 1).

As best seen in Figure 1, lever 22 has pivotally secured thereto at 30 a lug 31 having a ledge 32

2

adapted to selectively engage a counter lever 33 operatively connected to spring return ratchet reset counter 34. A stop pin 35 on lever 22 is adapted to engage lug 31.

5 A second lug 36 is pivotally connected at 37 to lever 22 and has a ledge 37' adapted to selectively engage a counter lever 38 operatively connected to spring return ratchet reset counter 39. A stop pin 40 on lever 22 rides in a slot 40' in lug 36. A tension coil spring 41 is secured to lugs 31 and 36 to bias them toward engagement with stop pins 35 and 40.

Referring again to shaft 28, it will be seen in Figure 1 that it carries a boss 44, which is engaged by opening 46 in arm 48 so as to be freely rotatable therein. Arm 48 is integral with bar member 49. Bar member 49 is slidably engaged by bracket members 50 and 51. A spring clip 52 secured to bracket member 51, engages arm 48. Bar member 49 carries a pair of blocks 53 and 54, which are pivotally secured to bar 49 at 55 and 56, respectively. A coil spring 57 urges blocks 53 and 54 together. The travel of blocks 53 and 54 together, as urged by the spring 57 is limited by block 58, which is secured to bar 49. The bar 49 has a manipulating handle 49'.

20 A block 59 is fixedly secured, as by welding, to a bar 60 which is slidably held within bracket 61 secured to base 4. Block 59 has a bar 62 extending rearwardly therefrom to an opening 63 in block 64, which is secured to base 4.

25 A coil spring 65 has one end secured to block 64 and the other end secured to screw 66 on block 59. Spring 65 passes through opening 67 in reset handle 68. Spring 65 urges the block 59, bar 62 and bar 60 rearwardly, as viewed in Figure 1.

30 As seen best in Figure 3, block 59 has a cut-out portion 69 which is adapted to receive block member 53 or block member 54 when block 59 is appropriately positioned.

An arm 70 (Figure 1) is fixedly secured to block 59 and carries thereon a finger 72, the finger 72 being secured to arm 70 by means of a hinged connection shown at 74. Finger 72 extends downwardly to a point in the vicinity of trip arm 6, and has at its outermost end a substantially horizontal surface 76 which is inserted in stack under last article counted when counters are switched.

35 Finger 72 is in the non-operating position due to the fact that block 59 is being held in a fixed position by block 54, which, as will be seen from Figure 1, is in opening 69 and thus holds block 59

in a fixed position, despite the force of spring 65 which is trying to move block 59 rearwardly.

It is well known to elevate, for example, envelopes past a trip arm such as 6, which is connected to a single counter. Numerous mechanisms for raising or elevating envelopes, or other articles to be counted, past a counter trip arm, are known to the art. It is, therefore, not necessary to go into any great detail with respect to mechanism used to elevate and support the envelopes 8. In Figure 1 there is shown in part an envelope deposit station 80 which is of the same essential structure as the deposit station disclosed in Patent No. 2,325,455 issued July 27, 1943. A conveyor chain 82 carrying a holding clip 84 is shown in Figure 1, which also shows a platen 86 utilized to elevate each envelope 8 after it has been placed on the platen by conveyor chain 82. In Figure 5 is shown a portion of a support member 90 for platen 86, which spans the conveyor chain. After the envelopes are raised they drop back onto hinged flaps 92.

Platen 86 has a cut-out portion 93 to permit it to pass by arm 6 and a second cut-out portion 94 to permit passage by finger 72 when it is extended rearwardly. Vertical guide bars 96 hold the envelopes in position in the stack.

As will be readily apparent, the deposit station of Patent No. 2,325,455 may be readily used, needing only to be modified to permit the lifting platen to pass freely by arm 6 and finger 72.

The invention here will be further illustrated by a description of the operation of the embodiment of the invention shown in the figures. Before the envelopes 8 are stacked, bar 49 is adjusted to have one of the ledges 32 or 37' engage a counter lever, for example, the lever 33 as engaged by ledge 32 as the parts are shown in the figures. Block 59 and bars 60 and 62 are then moved against spring 65 until spring 57 pulls block 54 within opening 69 so as to engage block 59. Stacking of letters 8 will then be commenced using platen 86. As each envelope 8 is passed upwardly, it moves trip arm 6 about rod 10, which results in the downward movement of lever 12 and lever 14 to actuate counter 16. It will be noted that counter 16 is always in operation and thus maintains a total count of all the envelopes stacked. As the parts are shown in the figures, the rotation of lever arm 6 moves lever 20 counterclockwise, as shown in Figure 5, moving lever 22 to the left, which in turn rotates lever 26 and rod 28 counterclockwise, as viewed in Figure 5, resulting in the actuation of lever 33 by ledge 32 to show a count on counter 34. The spring return of counter 34 restores these elements to their normal position. When a stack of envelopes of the desired number, as shown by counter 34, has been made, bar 49 is pulled to the right, as viewed in Figure 1, to carry arm 48, rod 28 and lever 22 to the right to effect the engagement of ledge 37' with lever 38, and thus place counter 34 out of operation and counter 39 in operation. Subsequent operation of counter 39 is effected in exactly the same manner as the previously described operation of counter 34. The pivotal connections between lever 22 and levers 20 and 26 have sufficient play to allow for the sidewise movement of levers 22 and 26.

The shifting of bar 49 to the right carries block 54 sufficiently far to the right so that it is wholly removed from opening 69, thus permitting spring 65 to move block 59 and its associated elements rearwardly, as viewed in Figure 1, which in turn

moves arm 70 and finger 72 rearwardly so as to interpose finger 72 under the last envelope counted by counter 34. The operator will then remove all of the envelopes 8 above finger 72.

The operator will now reset counter 34 to zero and will pull block 59 against spring 65, which will permit the entry of block 53 into opening 69, to hold block 59 against spring 65 and place finger 72 in a disengaged position.

After the proper count is shown on counter 39, bar 49 will be pushed to the left, as viewed in Figure 1, resulting in the disengagement of ledge 37' with lever 38, and reengagement of ledge 32 and lever 33, to place counter 39 out of operation and counter 34 back in operation. This will also result in the release of block 53 from opening 69 in block 59, which, in the manner previously described, will cause finger 72 to be placed under the last envelope counted by counter 39, thus permitting the accurate removal of the newly counted stack of envelopes.

The pivotal arrangement of lugs 31 and 36 with spring 41 permits smooth operation if bar 49 is moved during a period when lever 22 is in motion, since when the lugs are pulled against, for example, a counter lever, they will be freely rotated, snapping back into position when the lever 22 returns to its rearward position.

Spring clip 52 is used to keep bar 49 from moving out of the selected position incident to vibration, or the like.

It is not desired to be limited except as set forth in the following claims, the above description being by way of illustration only.

What is claimed is:

1. A machine for counting articles being stacked, which comprises a lever pivotally mounted to have one end thereof in the path of the articles being stacked and adapted to be pivoted by the passage of each article, a pair of spring return reset counters, means to selectively engage said pivoted lever with said counters, a finger adapted to be interposed between the articles being stacked, said finger being operatively engaged with said means to effect the interposition of the finger between the articles being stacked when said means is operated to shift from one counter to the other, and means to independently retract said finger from between the articles being stacked.

2. A machine for counting articles being stacked, which comprises a lever pivotally mounted to have one end thereof in the path of the articles being stacked and adapted to be pivoted by the passage of each article, a pair of spring return reset counters, a second lever connected to said first mentioned lever and having lugs adapted to selectively engage said counters, respectively, means to move said second lever to effect the selective engagement of said lugs with said counters, a finger adapted to be interposed between the articles being stacked, said finger being operatively engaged with said means to effect the interposition of the finger between the articles being stacked when said means is operated to shift from one counter to the other, and means to independently retract said finger from between the articles being stacked.

3. A machine for counting articles being stacked, which comprises a lever pivotally mounted to have one end thereof in the path of the articles being stacked and adapted to be pivoted by the passage of each article, a pair of spring return reset counters, a second lever connected to said first mentioned lever and having

lugs adapted to selectively engage said counters, respectively, means to move said second lever to effect the selective engagement of said lugs with said counters, said lugs being pivotally mounted, spring means to bias said lugs into operative position, a finger adapted to be interposed between the articles being stacked, said finger being operatively engaged with said means to effect the interposition of the finger between the articles being stacked when said means is operated to shift from one counter to the other, and means to independently retract said finger from between the articles being stacked.

4. A machine for counting articles being stacked, which comprises a lever pivotally mounted to have one end thereof in the path of the articles being stacked and adapted to be pivoted by the passage of each article, a pair of spring return reset counters, means to selectively engage said pivoted lever with said counters, a 10 slidable member, a finger pivotally secured to said slidable member, a spring adapted to move the slidable member to a position so as to interpose said finger between the articles being stacked, stop means to selectively hold said slidable member against the spring to maintain the finger in an operative position, said stop means being operatively connected to said first mentioned means so as to effect the release of

the slidable member on actuation of said first mentioned means and means to effect the engagement of said stop means independent of the movement of said first mentioned means.

5. A machine for counting articles being stacked, which comprises a lever pivotally mounted to have one end thereof in the path of the articles being stacked and adapted to be pivoted by the passage of each article, a pair of 15 spring return reset counters, a second lever connected to said first mentioned lever and having lugs adapted to selectively engage said counters, respectively, a slidably mounted bar connected to said second lever and adapted to effect the selective engagement of said lugs with said counters, a slidably mounted block, a finger pivotally secured to said block, a spring adapted to slide said block to interpose said finger between articles being stacked, a pair of block members 20 pivotally secured to said bar and adapted to selectively engage an opening in said first mentioned block to hold the pair of blocks against the spring, the movement of said bar effecting the disengagement of the blocks and the actuation of the spring.
